UNITED STATES PATENT OFFICE.

BENEDIKT HOLZMAYER, OF BERLIN, GERMANY, ASSIGNOR TO DEUTSCHE LUXFER
PRISMEN GESELLSCHAFT M. B. H., OF BERLIN, GERMANY, A CORPORATION OF
GERMANY.

SIGN.

Application filed August 12, 1921. Serial No. 491,800.

(GRANTED UNDER THE PROVISIONS OF THE ACT OF MARCH 3, 1921, 41 STAT. L., 1313.)

To all whom it may concern:

Be it known that I, BENEDIKT HOLZMAYER, a citizen of Germany, and resident of Berlin, Germany, have invented certain new and useful Improvements in Signs, for which I have filed applications in Germany January 13, 1919, December 29, 1920, and March 27, 1920, and of which the following is a specification.

10 This invention relates to signs having individual characters, and is particularly intended for use on building shops, stores, etc., for the purpose of displaying indications of the owner's name, the name or 15 number of the house or street, and so forth. Signs of this type employed hitherto have the objectionable feature of showing plainly the joints between the individual plates bearing the characters, thus giving the sign 20 an unattractive and "cheap" appearance, and detracting from its selling value. My present invention enables me to produce signs consisting of plates or sections and yet producing the impression of a neat sign 25 made of a single piece. Another advantage of the invention resides in the possibility of making strong individual plates or sections from relatively thin material for instance light sheet metal. For the purposes indicated 30 the exposed surfaces of the individual plates or sections are grooved or corrugated, in the manner explained hereinafter. The novel features of my invention are pointed out in the appended claims.

35 Reference is to be had to the accompanying drawings illustrating two satisfactory and preferred embodiments of my invention. Fig. 1 is a perspective face view showing a portion of a sign constructed according to 40 my invention; Fig. 2 is a horizontal section on line 2—2 of Fig. 1; Fig. 3 shows in face view, three different character-bearing plates or sections; and Fig. 4 is a vertical section showing another form of my invention.

45 In Fig. 1, I have indicated an end section *a* in connection with one of the unit-sections *b* of which the character-bearing portion of the sign is composed. These unit-sections, of different width as required by the particular character thereon (see Fig. 3), are made with vertical grooves *c* on their exposed surface, the character-bearing por-

tion of each unit being preferably corrugated vertically for this purpose, as shown 55 best in Fig. 2. Each unit-section is also provided, at the top and at the bottom, with a portion *d* of greater thickness, adapted to form part of the frame-like outline of the sign. These portions *d* are also made with 60 vertical grooves *e*, preferably in alignment with some of the grooves *c*. The end section *a* has vertical grooves *c'* of the same character as the grooves *c*, the body of said end section being preferably corrugated for 65 this purpose, and said section also has frame portions *d'* at its top and bottom edges, and a vertical frame portion *d''* at its outer side edge. The frame portions *d'* have vertical 70 grooves *e'* similar to the grooves *e*. It will be noted that the character-bearing units *b* have their vertical side edges at the deepest 75 points of two of the grooves *c*, that is to say, there is a half-groove *c* at each edge. Thus when two such units *b* are fitted together, the joint between them will be inconspicuous. Furthermore, when the grooves 80 *c* and *c'* are of the same width and form, as shown, the joint *f* between the end section *a* and the adjacent unit section *b* will likewise be inconspicuous. It will be seen by reference to Fig. 2, that the joint between an end section *a* and the adjacent unit-section *b* is a butt-joint.

The grooving or corrugating of the plates 85 or body portions of the sections *a* *b* also has the advantage of increasing their strength materially, so that sections of substantial rigidity may be made from thin material, for instance light sheet metal. 90

It will be understood that each sign will 95 comprise a left-hand end section such as *a*, a corresponding right-hand end section, and one or more intermediate character-bearing sections such as *b*. The several sections composing the sign will be fastened in any suitable manner to the building or other structure or article carrying the sign. With a proper set of unit sections, various combinations may be formed readily, yet a sign so built up will have practically the same appearance as a more expensive sign made of a single piece. Even when the individual sections *b* are of different widths (see Fig. 3), this will not be noticed except upon a very careful inspection such 100 105

as the ordinary observer will never give to the sign.

In the form of my invention illustrated by Figs. 1, 2 and 3, the letter or other character borne by a unit-section *b* is secured thereto rigidly or permanently. In Fig. 4 I have shown a construction in which the unit-sections *b'* do not carry the characters permanently, but are provided with registering or mating horizontal guides or grooves *g* to receive sliding characters which may be of any well-known or approved type suitable for this purpose. The section *b'* would be similar to the section *b* as regards the provision of vertical grooves such as *e*, *e* in Figs. 1, 2 and 3. The sections *b'* would form a carrier for the letters or other characters, and could be secured to the wall *h* or other support, for instance by means of wooden laths *i*, while the sliding characters could be inserted or removed without disturbing the other parts of the sign, so that the wording or other indication of the sign could be changed readily.

The sections *a*, *b*, *b'* of the sign may be made of glass, ceramic material, fancy brick etc. In this case the sign (including its frame, if desired) will consist of weatherproof, non-rusting material. Since no special metal frame is required in this case, the sign will have a harmonious unitary appearance, and it will thus be possible to make the sign conform to the style of architecture of the house, etc.

Various modifications may be made without departing from the nature of my invention as set forth in the appended claims.

I claim as my invention:

1. A sign of the class described, comprising a plurality of individual sections provided with grooves in their exposed surfaces, to render the joints between said sections

inconspicuous and to strengthen said sections.

2. A sign of the class described, comprising a plurality of individual sections located side by side and provided, on their exposed surfaces, with grooves parallel to the joints between adjacent sections. 45

3. A sign of the class described, comprising a plurality of individual sections each having a body provided with grooves, and frame portions likewise provided with grooves. 50

4. A sign of the class described, comprising a plurality of individual sections each having a body provided with grooves, and frame portions likewise provided with grooves, the last-named grooves being in alignment with grooves of the body. 55

5. A sign of the class described, comprising a plurality of individual sections having parallel corrugations of like shape, the edge of one section being fitted into a corrugation of the adjacent section. 60

6. A sign of the class described, comprising end sections each having a body, frame portions at opposite edges of said body, and a frame portion connecting the first-named frame portions, and one or more intermediate sections fitted between said end sections and provided, at opposite edges, with frame portions aligning with the first-named frame portions of the end sections. 70

7. A sign of the class described, comprising individual sections located side by side and provided, in their exposed surfaces, with grooves parallel to the joints between adjacent sections, the side edge of one of said sections coinciding with the deepest portion 80 of one of said grooves. 75

In testimony whereof I have signed this specification.

BENEDIKT HOLZMAYER.
